PIVOTED CHARGING SUBCHUTE FOR CONCRETE MIXERS

Filed June 1, 1927

FIG. 2.

FIG. 1.

CHARLES F BALL

By *John S. Parker*

Attorney

UNITED STATES PATENT OFFICE.

CHARLES F. BALL, OF MILWAUKEE, WISCONSIN, ASSIGNOR TO CHAIN BELT COMPANY, OF MILWAUKEE, WISCONSIN, A CORPORATION OF WISCONSIN.

PIVOTED CHARGING SUBCHUTE FOR CONCRETE MIXERS.

Application filed June 1, 1927. Serial No. 195,740.

This invention relates to charging devices for concrete mixing machines and similar apparatus, and consists particularly in a pivoted sub-chute, that is to say, a chute or spout 5 that is interposed between the delivery opening into the mixing drum and the discharge lip or spout of the charging skip, when the latter is moved into position to deliver its charge to the mixing drum.

10 In the accompanying drawings,

Fig. 1 is a side view illustrative of my invention, as applied to a concrete mixer of well known construction, part of the mixing drum being broken away.

15 Fig. 2 is a transverse vertical section taken on the line II—II of Fig. 1.

It will be understood that many of the parts of a concrete mixing apparatus to which my invention is applied are not illustrated in 20 the drawings, as the particular details of such machine may be varied within wide range without affecting the principle of the invention.

Referring to the drawings, 2 designates the 25 supporting framework of a concrete mixing machine, the front end only of which is shown. 3 indicates the drum of such machine and 4 the loading skip therefor. The latter is represented as being provided with a 30 pair of pivoting arms 11 through which pass the shaft 5 constituting an element of the pivotal support for the loading skip. Directly in front of the charging opening into the drum, and supported by the framework 35 in close relation thereto, is the front shield 6 which is very commonly employed in machines of the character illustrated. Through such shield is formed a charging opening that registers with a charging opening into the 40 drum.

It has heretofore been common practice to secure to the shield 6 a short spout or chute for directing the material from the delivery end of the skip 4 into the drum. This sub-chute has heretofore necessarily been quite 45 short, in order not to interfere with the nose or delivery end of the charging skip, which travels in the arc indicated by dotted lines in Fig. 1. It has also been found necessary 50 to support each sub-chute at an angle considerably less than that assumed by the charging skip when in the act of delivering to the drum, with the result that the material delivered will not always slide freely from the 55 sub-chute but will tend to collect therein,

making it necessary that a workman should frequently clear the sub-chute manually of material lodged therein. One of the purposes of my invention is to permit the use of a longer sub-chute than it has heretofore been 60 practical to employ, and one which is adjustable, so that it may be caused to assume a very steep or sharp angle of inclination insuring free delivery of the material that might otherwise tend to lodge therein. 65

Referring again to the drawings, 8 indicates a sub-chute made according to my present invention. This is pivotally supported, being connected with the front shield 6 by a pivot shaft 9. 70

The pivoting arms of the loading skip are extended beyond the pivot shaft 5 to form heel extensions 10 in the ends of which is supported a cross shaft 12. A link 13 connects the shaft 12 and the pivoted sub-chute. 75

On either side of the sub-chute are stationary wings 14, between which the chute lies when moved to its uppermost position, and between which the skip lies when in its charging position. 80

15 indicates the cables by which the skip is operated in a well known manner. When the loading skip is in its lowered position, resting upon the ground to receive its charge, as represented in full lines in Fig. 1, the sub-chute is held, by the link 13, in its raised position, lying between the stationary wings 14, with its inner end extending well into the mixing drum, and having its bottom inclined at so steep an angle that any material, which 90 may have been delivered to such chute, will slide over the bottom and into the drum. As the skip is elevated into charging position the sub-chute is lowered, through its connection with the heel extensions of the pivoting 95 arms of the skip, until the sub-chute assumes the position shown in dotted lines when the skip is raised to its highest position and discharges its load. It will be seen that the sub-chute now extends well under the nose or 100 spout end of the skip, lapping the same for a considerable distance, and that its angle of inclination is much less than that which it had when in the position first described. It will be seen from a comparison of the two 105 positions of the sub-chute indicated in the drawing that the length of the sub-chute, that is of the bottom portion thereof, is considerably greater than could be a stationary 110 chute that occupied the angular position rep-

resented in full lines. The drawing shows that the arc followed by the nose of the loading skip cuts the bottom of the sub-chute when in its upper position some considerable distance below its rear end. The sub-chute occupies a steep inclined position during the time that the skip is down for loading, with the result, as has been stated, that material, that might have lodged and remained on the bottom of the chute had it continued in the position indicated in dotted lines, will slide into the mixing drum. Further, by increasing the length of the bottom portion of the sub-chute, made possible by the arrangement described, such chute serves to prevent the material being mixed in the drum from splashing out through the charging opening, in a much more effective manner than when a shorter and less inclined sub-chute is employed as has heretofore been customary.

While I have illustrated and described my present invention in connection with a concrete mixing machine, I wish it to be understood that such invention is not limited in its useful applications to the particular arrangement shown or used in connection with the particular type of machines illustrated.

What I claim is:

1. The combination with a receptacle provided with an opening through which it may be charged, of a loading skip arranged to be moved from a position to receive its charge to a position to deliver the same into the receptacle through the charging opening, means serving as a chute through which the material delivered from the loading skip is directed through the charging opening into the receptacle supported so as to be moved into a position to cover the charging opening, such means when in said position being in the path of movement of the loading skip, and means for moving the first said means into the covering position when the skip is in non-delivery position, and for moving it out of the way of the skip when the latter is moved to delivery position.

2. The combination of a receptacle provided with an opening through which it may be charged, of a loading skip arranged to deliver through the said charging opening, means serving as an intermediate chute between the loading skip when in delivery position and the said receptacle supported so as to be moved into a position to cover the charging opening, means for moving the first said means into the covering position when the skip is in non-delivery position and into position to deliver material from the loading skip through the charging opening when the skip is in delivery position, and wings between which the covering means is located when in covering position and between which the end of the charging skip lies when it is in delivery position.

3. The combination with a receptacle pro-

vided with an opening through which it may be charged, of a pivotally supported loading skip arranged to deliver through the said charging opening, a sub-chute supported on a pivot remote from the pivot of the loading skip so as to be moved into a position to serve as a chute intermediate the skip and the receptacle when the skip is in its delivery position, and means for moving the sub-chute into the said intermediate position as the skip comes to delivery position.

4. The combination with a receptacle provided with an opening through which it may be charged, of a pivoted loading skip arranged to deliver through the said charging opening, a pivoted sub-chute arranged to occupy a position between the loading skip and the receptacle and to serve as an intermediate delivery chute between these parts, the sub-chute being also arranged to be moved into a position to cover the charging opening, and means for moving the sub-chute into the covering position when the skip is in non-delivery position, and into the intermediate position to serve as a delivery chute when the skip is in delivery position, the pivotal supports of the loading skip and the sub-chute being non-coaxial.

5. The combination with a receptacle provided with an opening through which it may be charged, of a loading skip arranged to deliver through the said charging opening, the skip being provided with arms by which it is pivotally supported, the arms being continued beyond the pivot to form heel extensions, a sub-chute occupying an intermediate position between the end of the charging skip and the receptacle when the former is in delivery position, and connections between the said heel extensions of the pivoting arms of the skip and the sub-chute, whereby the latter is moved into operative positions as the skip is moved.

6. The combination with a receptacle to be charged, of a loading skip arranged to deliver to the receptacle, a sub-chute pivotally supported near the receptacle and connections between the sub-chute and the loading skip whereby the sub-chute is moved as the skip is moved, the sub-chute being arranged to be moved into a position covering the charging opening into the receptacle when the loading skip is in its non-delivery position, the sub-chute when in this position being located in the path of movement of the delivery end of the charging chute, and the sub-chute being further arranged to be moved out of the path of the said delivery end of the loading skip and into position to serve as an intermediate chute between the end of the loading skip and the receptacle when the charging skip is moved to delivery position.

7. The combination with a receptacle provided with an opening through which it may be charged and a pivoted charging skip

- therefor, of an independently pivoted sub-chute extending into the charging opening of the receptacle and arranged to occupy an intermediate position between the delivery 5 end of the skip and the receptacle when the skip is in delivery position, and means operated by the skip for moving the sub-chute into position to serve as a cover for the charging opening into the receptacle when the skip 10 is down being loaded, and into position to serve as an intermediate chute when the skip is raised to discharge its load.
8. The combination with a receptacle to be charged and a movable loading skip therefor, 15 of a pivoted sub-chute arranged to occupy a position between the receptacle and the skip, and means controlled by the movements of the skip for moving the sub-chute into an intermediate inclined position between the 20 skip and the receptacle to serve as a chute for the material delivered from the skip when the latter is moved to delivery position, and for moving the sub-chute to a steeper inclination as the skip is lowered to its charging 25 position.
9. The combination with a receptacle provided at one end with a charging opening and a loading skip therefor, of a plate or shield supported close to and in front of the charging end of the receptacle and formed 30 with an opening registering with the charging opening into the receptacle, a sub-chute pivoted to the said plate and extending through the said openings into the receptacle, 35 and connections through which the sub-chute is operated from the loading skip, the chute being arranged to occupy an intermediate position between the receptacle and the end of the skip when the latter is in its raised 40 position to discharge, and a different and more sharply inclined position when the skip is lowered for loading.
10. The combination of a receptacle formed with a charging opening, a loading skip 45 having arms through which the skip is pivotally supported, the arms being extended to
- form heel extensions, a shield through which is an opening registering with the charging opening of the receptacle, supported close to the charging end of the receptacle, a sub-chute pivotally connected with the shield and having one end extending through the said openings into the receptacle and its other end extending outwardly so the sub-chute may occupy an intermediate position between the 55 skip and the receptacle, a link connection between the sub-chute and the heel extensions of the pivot arms carried by the loading skip and stationary wings carried by the shield on opposite sides of the opening through the 60 same, the said parts operating as described.
11. The combination with a receptacle formed with a charging opening, of a loading skip supported upon one pivot and arranged when elevated to deliver material by 65 gravity to the receptacle, a sub-chute supported upon another pivot and arranged to bridge the space between the end of the loading skip and the charging opening into the receptacle when the skip is elevated, and 70 to occupy a position in the path of the discharge end of the loading skip and between such end and the delivery opening when the loading skip is lowered to receive its charge, and means between the charging skip and the 75 sub-chute whereby the latter is moved to occupy the positions stated as the loading skip moves from charging to discharging position and return.
12. The combination with a receptacle, of 80 a loading skip therefor and a movable sub-chute arranged to occupy a position between the delivery end of the loading skip and the receptacle when the skip is raised to discharge its load by gravity, and means arranged to 85 increase the delivery angle of the chute after the skip has delivered its load whereby residual material that may remain in the sub-chute is caused to flow into the receptacle by gravity.
